SWITCH

Filed July 30, 1928

Inventor:
Albert R. Locke.

By: Charles ~~McVay~~ McVay

UNITED STATES PATENT OFFICE

ALBERT R. LOCKE, OF OAK PARK, ILLINOIS

SWITCH

Application filed July 30, 1928. Serial No. 296,395.

This invention relates to improvements in switches for the closing or opening of electrical circuits, and more particularly to a switch incorporating therein means for the snubbing or extinguishing of any arc created by the manipulation of the switch mechanism, although the device may be used for many and varied purposes as will be apparent to one skilled in the art.

10 In the past, various means and devices have been employed for the extinguishing of an arc caused by the actuation of switch mechanism or the like, but these formerly known instrumentalities have, in most instances, proven objectionable due to the fact that they were not as intimately associated with the various contacts of the switch mechanism as is desirable, were not as durable, nor as effective in their action as is desirable, 20 and frequently were constructed of mechanism such as becomes sluggish in its action after comparatively short usage. Moreover, the means for this purpose heretofore known were frequently prohibitively expensive for 25 utilization in practically every type economical installation.

The present invention is designed to overcome the above noted as well as other defects and objections in the provision of a 30 switch or switch mechanism provided with arc snubbing means which positively and effectively extinguish any arc caused by the manipulation of the switch mechanism.

Another object of the present invention is 35 to provide a switch equipped with arc snubbing means which are movable with the movable contact of the switch in either direction.

Another object of the present invention is 40 to provide arc snubbing means for a bridging contactor which substantially embraces said contactor and extends therebeyond in a plurality of directions so that the snubbing means will at all times lie within the path of an arc caused by the action of the contactor relative to the contacts of the switch.

A still further object of the present invention is to provide a switch equipped with a movable contacting element provided with arc snubbing means movable therewith, there 45 being no sharp corners on the structure to

become scored or otherwise affected by arcs resulting from the manipulation of the switch mechanism.

A still further object of the present invention is to provide a device of the character described herein, which is durable, positive in its action, and readily and easily assembled. 55

While some of the more salient features, characteristics, and advantages, of a device embodying the present invention have been 60 above pointed out, others will become apparent from the following disclosure.

The invention includes these and other features of construction and combinations of parts hereinafter described, and shown in a 65 preferred form in the drawings, as more particularly by the claims.

Referring to the drawings, Figure 1 is a fragmentary view in elevation of a switch unit provided with means embodying principles of the present invention. 70

Figure 2 is an enlarged fragmentary view in elevation, with parts omitted, of a portion of the structure shown in Figure 1.

Figure 3 is a view in elevation showing the 75 interior of a part of the arc snubbing means.

Figure 4 is an enlarged bottom plan sectional view taken substantially along line IV-IV of Figure 1.

In the structure arbitrarily selected to illustrate an embodiment of the present invention there is shown a base plate 1 on which is mounted switch mechanism including parallel upright frame members 2 which effectively support a housing 3 and a front 4. 80 Mounted on the plate 1, in any desirable manner, on each side of the frame members 2, is a pair of spaced contact members 5 suitably connected to adjacent binding posts 6. A double throw switch element including an arm 7 and a handle 8 is pivotally mounted in the housing 3 by means of an arcuate portion 9 properly seated in the upper part of the housing 3 with the aid of pins 10. 85

The lower end of the switch arm 7 is bifurcated to form a pair of arcuate furcations 11. In the present embodiment, an arc snubbing element is provided, which is formed from a pair of complementary disk portions 12 and 13, respectively, formed from any desirable 90

nonconductive and nonignitable material such as asbestos compound, and each of which is recessed as at 14 (Figure 3) on their inner faces to accommodate a portion of the arm 5 7 and the furcations 11, so that when both disks, 12 and 13, are seated together the furcations will be securely imbedded therebetween as seen more clearly in Figures 2 and 4. The disks 12 and 13 are also provided 10 with a central aperture 15 to receive therethrough a contactor embodying a pair of conductive members 16 and 17, respectively, in this instance, the member 16 having a central pin 18 projecting inwardly therefrom so 15 as to be telescopically received within an integral bushing 19 on the element 17. The outer faces of the members 16 and 17 are flanged so as to provide a suitable contactor for bridging the contacts 5 by passing therebetween as shown clearly in Figure 4. The 20 disks 12 and 13 are recessed on their outer faces, as at 20, to accommodate substantially half of the flanged portions of the elements 16 and 17. The telescopic joint uniting the 25 elements 16 and 17, in this instance, is shown as a forced fit joint and will effectively hold all of the elements in their proper relation on the furcations 11. It is to be understood, however, that the contact elements 16 and 17 30 may be united in any desired manner or may be formed in one single piece, and the arc snubbing means also may be formed in one piece and secured around the contactor in any desired manner. 35 It will be equally apparent that the arc snubbing element need not be in the form of a disk, but this form is preferable in view of the fact that when the peripheral edges of the arc snubber are rounded, as at 21, and the peripheral edges of the elements 16 and 40 17 are rounded, as at 22, there are no resulting sharp corners to be scored or pitted by any arcs which may be produced, it being well known that sharp corners on any structure similar to that described herein, provide a material fire hazard, in view of the fact 45 that an arc will strike or make readily with a sharp corner or point.

To operate the present invention, the handle 8 is merely thrown in either of the directions shown by the dotted lines in Figure 1, so that the contactor will bridge either of the pairs of the spaced contacts 5, thereby establishing electrical connection between the contacts. If any arcs are created by the proximity of the contactor to the contacts 5, the arc snubber formed from the disks 12 and 13 55 extending beyond the contactor in all directions, when actuated will first pass directly in the path of the said arc and snub or extinguish the same. The same is true when the contactor leaves the contacts 5, there being a portion of the arc snubber remaining in the path of the arc, if such be produced, after 60 all the conductive elements have separated.

From the foregoing, it will be apparent that I have provided arc snubbing means movable with the contactor of the switch mechanism and so disposed as to positively snub any arc which may be produced by the movement of the contactor relative to the contacts of the switch. Moreover, the present invention is extremely durable and may be easily and economically manufactured and assembled.

I am aware that many changes may be made and numerous details of construction may be varied through a wide range without departing from the principles of this invention and I, therefore, do not purpose limiting the patent granted hereon otherwise than necessitated by the prior art.

I claim as my invention:

1. In a switch, a pair of spaced contacts, a pivoted switch blade, a round contactor having external rounded edges carried by said blade for selectively bridging said contacts to establish electrical connection therebetween, and a non-conductive and non-ignitable disc of larger diameter than said contactor and movable therewith for extinguishing arcs between said contacts and said contactor, said contactor extending axially beyond the surface of said disc.

2. In a switch unit, spaced contacts, means for bridging said contacts including a pair of telescopically joined conductive members having flanged outer portions for engagement with said contacts, and an arc snubbing element disposed between said flanged portions, whereby said conductive members and said element may be dismantled at will.

3. In a switch, spaced contacts, a pivoted blade having a bifurcated end, non-conductive non-ignitable discs having recesses therein to accommodate the furcations on said blade, said discs being centrally apertured, and conductive means passing through the apertures in said discs for conductive engagement with said contacts.

In testimony whereof I have hereunto subscribed my name at Chicago, Cook County, Illinois.

ALBERT R. LOCKE.
